United States Patent

Des. 236,415
Patented Aug. 26, 1975

236,415

SKILLET

Gunnar Cyren, Gavle, Sweden, assignor to Dansk
International Designs Ltd., Mount Kisco, N.Y.

Filed Feb. 28, 1974, Ser. No. 447,112

Term of patent 14 years

Int. Cl. D7—02

U.S. Cl. D7—95

FIG. 1 is a top plan view of a skillet showing my new design;
 FIG. 2 is a side elevational view thereof;

FIG. 3 is a front elevational view thereof;
 FIG. 4 is a rear elevational view thereof; and
 FIG. 5 is a bottom plan view thereof.

I claim:

The ornamental design for a skillet, as shown.
